UNITED STATES PATENT OFFICE.

CLARENCE WALLACE TAYLOR, OF JANEVILLE, WISCONSIN.

FOUNTAIN-PEN.

SPECIFICATION forming part of Letters Patent No. 320,509, dated June 23, 1885.

Application filed November 14, 1884. (No model.)

To all whom it may concern:

Be it known that I, CLARENCE W. TAYLOR, of Janesville, in the county of Rock and State of Wisconsin, have invented certain new and useful Improvements in Fountain-Pens; and I do hereby declare the following to be a full, clear, and exact description of the invention, such as will enable others skilled in the art to which it appertains to make and use the same.

10 My invention relates to an improvement in fountain-pens.

Hitherto the construction of the so-called "fountain-pens" has been such as to require the use of thin watery ink, as the inks in common use have more or less sediment and, after a time, become thickened, and render the use of hair-like tubes for fissures inefficient and unsatisfactory. Again, it has been necessary to use pens of a special construction, which 15 may not be suited to the writer's particular needs. The supply and flow of the ink has also been unsatisfactory under various circumstances, and the popularity which attended their introduction has gradually diminished as their defects have become apparent.

The object of my present invention is to provide a simple, cheap, and durable fountain-pen, which can be adjusted to operate well 20 when held at any required angle in the hand of the writer, with any ordinary ink, and with either a steel or gold pen of ordinary construction, a further object being to provide a reservoir adapted to supply the pen with ink 25 without the use of valves or other movable machinery, thereby avoiding the liability to clog by the thickening of the ink and sediment.

With these ends in view my invention consists in certain features of construction and combinations of parts, as will be hereinafter described, and pointed out in the claims.

In the accompanying drawings, Figure 1 is a longitudinal sectional view of the pen and holder. Fig. 2 is an enlarged longitudinal section of the lower portion of the same. Fig. 3 is a transverse section through the line $x y$ of Fig. 1. Fig. 4 is a detached view of the adjustable bar, and Fig. 5 is a sectional view 30 of the cap.

A represents the barrel of the pen-holder,

provided with the reservoir a , adapted to receive ink of any ordinary make. The point-section B is fitted with a thread, b , on its upper end, adapted to engage a female thread, b' , in the lower end of the barrel A, by means of which the section B may be removed and adjusted, and the reservoir a be filled, cleaned, &c.

The section B is provided with a channel, 60 C, communicating freely with the reservoir a and with an ink well or receptacle, c , located at the lower end of B, by a small perforation or capillary tube, c' .

D is the pen. It is secured to the section 65 B by inserting its upper end in a suitable socket, d , and its lower or slotted portion, a short distance above the point, covers the well c . A slight space is left between the pen and point-section, above the well, to prevent the 70 ink from creeping up.

The section B is further provided with a longitudinal opening, E, extending from the reservoir a to the well c , in which an adjustable stop, F, is located. The stop F consists 75 of a bar smaller in cross-section than the opening E, and provided with bulk-heads ff' at the lower and upper ends, respectively, adapted to closely fit and slide within the opening E, forming air-tight joints. The 80 heads f and f' are provided with small perforations $e e'$, communicating with the open space E and the well c and reservoir a .

A perforation, G, is formed in the upper portion of the section B, extending from the 85 outside air to the upper portion of a longitudinal channel, g , formed in the back of the piece F, the said channel communicating with the well c through a perforation, g' , formed in the lower end of F.

A cap, H, provided with an internal lug or projection, h , is constructed to fit over the pen and lower section of the holder, the face of the projection h , when the cap is in position, being over the hole or slit in the pen, and the upper portion of the cap tightly closing the perforation G, thereby shutting out the air from contact with the ink in the well c , and preventing evaporation.

The operation of the pen is as follows: As 100 the pen is pressed upon the paper it recedes slightly from the well c , and the ink therein

flows downwardly toward its point ready for use. When the supply in the well *c* falls below the perforation *e* in the head *f*, air enters through the perforation *G*, channel *g*, and perforation *g'* into the well *c*, and from thence passes upwardly through the perforations *e* and *e'* into the reservoir *a*, and displaces a sufficient amount of ink to fill the well *c*, the ink passing into the well through the perforation or tube *e'*. As the ink enters the well *c* it closes the perforation *e*, and thereby stops a further displacement in the reservoir *a* until the ink in the well *c* is again used below the said perforation *e*.

15 The air in the opening *E* holds the ink in the reservoir and well in equilibrium so long as the perforations *e* and *e'* are closed thereby, and only enters through the perforation *e'* into the reservoir *a* when atmospheric pressure is 20 exerted through the perforation *G*, &c., as before explained.

The piece *F* is adapted to slide longitudinally in the opening *E*, and thereby determine the point at which the ink in the well *c* shall 25 fall below the opening *e*. Thus the pen may be held at different angles with the paper without changing the point at which the displacement in the reservoir takes place by simply adjusting the piece *F* up or down, as may be 30 necessary.

By the above construction the ink may be used to the last drop, the flow will be automatic and constant, and as there are no valves or movable parts to become clogged the pen 35 will retain its usefulness and remain in working order until the ink-reservoir is empty.

It is evident that slight changes may be made in the form and arrangements of the several parts described without departing 40 from the spirit and scope of my invention; hence I do not wish to limit myself strictly to the construction herein set forth; but,

Having fully described my invention, what I claim as new, and desire to secure by Letters Patent, is—

45 1. The combination, with a pen-holder and a pen, of an ink-reservoir located within the holder, an ink well or receptacle adapted to directly feed the pen, said well being connected with the reservoir by a capillary tube

for the passage of ink and by an air-chamber for the passage of air, substantially as set forth.

2. In a fountain-pen, the combination, with an ink well or receptacle adapted to directly 55 feed the pen and an ink-reservoir connected with the well by a capillary tube, of an air-chamber located between the well and reservoir and an adjustable perforated stop adapted to fit within the air-chamber, substantially as 60 set forth.

3. The combination, with the pen-holder and a pen, of an ink-reservoir located in the handle, an ink-well located immediately beneath the pen, said well being connected with 65 the outside air by a permanent opening and with the reservoir by a capillary tube for the passage of ink, and by an air-chamber for the passage of air, substantially as set forth.

4. The combination, with an ink-well located immediately beneath the pen, and an ink-reservoir adapted to furnish ink to the said well, of an adjustable double stop adapted to fit and slide within an opening between the well and the reservoir and admit air to 75 the reservoir at points suited to different angles of the holder, substantially as set forth.

5. The combination, with an ink-well and an ink-reservoir connected therewith by a capillary tube, of an adjustable stop located in 80 an opening between the well and the reservoir, provided with an air-channel adapted to transmit air from a perforation in the holder to the well and from the well to the reservoir, substantially as set forth.

85 6. The combination, with a pen-holder having an ink-well located immediately below the slit or hole in the pen, and provided with an ink-opening communicating with a passage from the ink-reservoir and an outside air-opening, of a cap adapted to completely cover the pen and close said outside air-opening, substantially as set forth.

In testimony whereof I have signed this specification in the presence of two subscribing witnesses.

CLARENCE WALLACE TAYLOR.
